BUTTER DISH

Herbert B. Hilton, 4724 Mount Durbun Drive,
Santee, Calif.

Filed June 17, 1963, Ser. No. 75,384

Term of patent 14 years

(Cl. D44—5)

Fig. 4

Fig. 5

I claim:
The ornamental design for a butter dish, as shown.
